(57) **CLAIM**

The ornamental design for shoe upper, as shown.

DESCRIPTION

FIG. 1 is a top plan view showing the new design;

FIG. 2 is a left side elevational view thereof;

FIG. 3 is a right side elevational view thereof;

FIG. 4 is a top plan view of the design detached from the shoe base; and,

FIG. 5 is a forward looking top plan view of the design.

The appearance of the shoe and components thereof is presented in broken line format and forms no part of the claimed invention.
